UNITED STATES PATENT OFFICE.

ELIZABETH SPRAGUE, OF MINNEAPOLIS, MINNESOTA.

CATAMENIAL NAPKIN.

1,195,621.

Specification of Letters Patent. Patented Aug. 22, 1916.

Application filed June 1, 1914. Serial No. 842,266.

To all whom it may concern:

Be it known that I, ELIZABETH SPRAGUE, a citizen of the United States, and resident of Minneapolis, in the county of Hennepin and 5 State of Minnesota, have invented certain new and useful Improvements in Catamenial Napkins, of which the following is a specification.

The object of this invention is to provide 10 a catamenial napkin or bandage that is inexpensive; that can be rolled up into a small, compact package so as to be capable of being sold from a coin operated machine; that is sanitary and easily applied and held 15 in position by a simple and single tape, without the use of straps, belts, buckles, buttons or harness of any kind; which is provided with a self-closing pocket in which suitable absorbent material is placed and in which it 20 is firmly held without the use of safety pins or other fastening devices, and in which the backing of the device is provided with a sheet of flexible rubber or similar impervious material which is completely inclosed 25 and surrounded so as to be incapable of coming in contact with the person of the wearer.

The invention consists generally in the constructions and combinations hereinafter described, and particularly pointed out in 30 the claims.

In the accompanying drawings forming part of this specification, Figure 1 is a perspective view of a device embodying my invention, Fig. 2 is a plan view of one of the 35 backing sheets with the rubber sheet secured thereto before the backing is folded and stitched. Fig. 3 is a similar view of the completed device, Fig. 4 is a transverse section on line 4—4 of Fig. 3.

40 In the drawings, 2 represents a sheet of material preferably of rectangular shape and formed of any suitable soft and pliable fabric. Upon one surface of this sheet I secure, preferably by stitching, a sheet 3, also 45 preferably rectangular, of soft rubber, or other suitable impervious, flexible material. This sheet of impervious material occupies the inner bottom surface of the self-closing pocket and is thus absolutely prevented from 50 coming in contact with the flesh of the person wearing the device. The sheet 2 is folded so as to form two flaps 4 and 5, extending preferably the full length of the sheet, the flap 4 being folded first and the 55 flap 5 being folded down on top of the flap 4. Transverse rows of stitches 6 and 7 are

then run through both flaps and the central section of the backing. The ends of the napkin are then finished, one end preferably by having an elastic loop 8 stitched into it and the other end being folded over and forming a transverse end loop 9. By this means a self-closing pocket 10 is formed between the rows of stitches 6 and 7. This pocket can be opened by lifting up the edge of the 60 upper flap 5 and pulling back the edge of the flap 4. The pocket can then be filled with absorbent cotton 11, or other suitable material, which will lie over the impervious sheet of material 3. The pocket is 65 completely self-closing owing to the fact that its ends are formed by the transverse rows of stitching and the flaps 4 and 5 are compelled to lie one over the other. No safety pins or other devices are required to hold 70 the absorbent material in place or to keep the pocket closed. The pocket naturally remains closed and the material is held therein when the device is in use. The sheet of impervious material 3 at the bottom of the 75 pocket prevents the discharge passing through the backing. The absorbent cotton can be quickly removed by opening the self-closing pocket and the cotton can be renewed at will. The napkin, with the cotton 80 removed, can be washed or laundered in the usual way. For holding the device in place, I preferably employ a tape 12 which passes through the transverse loop 9 and the elastic loop 8. 85

90 The device is exceedingly simple and is without any metal parts, such as buckles, buttons or safety pins. It can be rolled up into a small compass and sold through the medium of coin operated machines placed in 95 sleeping cars, and toilet and dressing rooms.

The device possesses an immense advantage in the fact that the rubber sheet is covered and protected from contact with the person of the wearer. The self-closing feature of the pocket is also of great value as thereby no safety pins, buckles, straps or other devices are required to hold the absorbent material in place, and this material can be removed and replaced at will. 100 105

The details of the construction may be varied in many particulars without departing from my invention.

I claim as my invention:

110 1. A device of the class described, comprising in combination a backing formed of a suitable fabric and provided with oppo-

sitely arranged flaps folded over the backing and overlapping each other, a sheet of impervious material secured to the backing on the inner face thereof, means for uniting 5 the flaps to the backing adjacent the ends of said impervious sheet and forming the end closures of a self-closing pocket, and absorbent material in said pocket.

2. A device of the class described comprising 10 in combination, a backing formed of a suitable fabric and provided with oppositely arranged flaps folded over the backing and overlapping each other, a sheet of impervious material secured to the backing on

the inner face thereof, transverse rows of 15 stitching extending across said flaps and backing adjacent the ends of said impervious sheet for uniting the flaps to the backing and forming the end closures of a self-closing pocket, and absorbent material in said 20 pocket.

In witness whereof, I have hereunto set my hand this 29th day of May 1914.

ELIZABETH SPRAGUE.
